UNITED STATES PATENT OFFICE.

JOHN VANDERCAR, OF WEST TROY, NEW YORK.

IRONING-MACHINE.

SPECIFICATION forming part of Letters Patent No. 234,631, dated November 16, 1880.

Application filed March 11, 1880. (No model.)

To all whom it may concern:

Be it known that I, JOHN VANDERCAR, of West Troy, in the county of Albany and State of New York, have invented a new and useful Improvement in Ironing-Machines, of which the following is a specification.

Figure 1 is a plan view of the improvement. Fig. 2 is a sectional side elevation taken through the line *x x*, Fig. 1. Fig. 3 is a side elevation, part being broken away.

Similar letters of reference indicate corresponding parts.

The object of this invention is to furnish machines designed especially for use in laundries for smoothing and drying collars, cuffs, and other articles, which shall be so constructed that the articles to be operated upon will be fed automatically into and through the machines, and which shall be simple in construction and effective in operation.

A represents the frame of the machine. B C are two rollers placed the one directly above the other. The journals of the roller C revolve in bearings in the frame A. The journals of the roller B revolve in vertical slots in uprights D, attached to the frame A.

Upon the journals of the roller B rest half-bearings E, upon the upper sides of which rest the lower ends of spiral or other springs, F.

Upon the upper ends of the springs F rest sliding blocks G, which are held down by screws H passing in through the caps of the uprights D, so that the force with which the roller B presses upon the roller C may be regulated by adjusting the screws H.

To the projecting end of one of the journals of the roller C is attached a crank wheel or pulley, I, by means of which motion is given to the machine by hand or by any other convenient power.

To the projecting end of the other journal of the roller C is attached a small gear-wheel, J, the teeth of which mesh into the teeth of a small intermediate gear-wheel, K. The teeth of the gear-wheel K mesh into the teeth of the small gear-wheel L, attached to the journal of the roller M, pivoted to the frame A upon a level with the lower roller, C.

To the forward end of the frame A is pivoted a roller, N, around which and the roller M

passes an endless apron, Q, which receives the articles as they pass out from between the rollers B C and carries the said articles out of the machine. The teeth of the gear-wheel J also mesh into the teeth of the small intermediate gear-wheel P, the teeth of which mesh into the teeth of the small gear-wheel Q, attached to a journal of the roller R. The roller R is pivoted to the frame A upon a level with and close to the lower roller, C, and around it passes an endless apron, S, which also passes around a pulley, T, pivoted to the frame A.

To the outer ends of the journals of the rollers C T are attached pulleys U V, around which passes an endless band, W, so that the roller T may be driven from the roller C.

To the journal of the roller T is attached a small gear-wheel, X, the teeth of which mesh into the teeth of a small intermediate gear-wheel, Y, pivoted to the frame A. The teeth of the gear-wheel Y mesh into the teeth of the small gear-wheel Z, attached to the journal of the roller a, which is pivoted to the inner part of the small frame b, and around which and around a roller, c, pivoted to the outer part of the frame b passes an endless apron, d. The frame b slides in a slot in the frame A, so that the said frame b may be moved inward to throw the gear-wheels Z Y into gear, and outward to throw the said gear-wheels out of gear.

e is a foot-lever attached to the outer end of a shaft, f, which rocks in bearings in the lower rear part of the frame A.

To the middle part of the rock-shaft f is attached an upwardly-projecting arm, g, the upper end of which is forked or slotted to receive a rod, h, attached to the outer end of the sliding frame b, so that the frame b may be moved inward to throw the gear-wheels Z Y into gear by operating the foot-lever e. The frame b is drawn outward when pressure is removed from the foot-lever e by a spring, i, attached to the base of the frame A, and which presses against the rod h.

The gear-wheels of the machine are all made of the same size, and the rollers are all made of the same size, so that the surfaces of the rollers B C and of the endless aprons O S d may move at the same rate of speed. The in-

termediate gear-wheels, K P Y, cause the endless aprons O S d and the lower roller, C, to all move in the same direction.

In using the machine the collars, cuffs, or other articles are spread out upon the endless apron d, and the frame b is moved inward by operating the foot-lever e to throw the gear-wheels Z Y into gear, so that the endless apron S will take the articles from the endless apron d and carry them forward and deliver them to the rollers B C, by which they are smoothed and pressed. As the articles pass out from between the rollers B C they are received upon the endless apron O and carried out of the machine.

j is a steam box or chest, into which steam is introduced from a boiler through the pipe k. The water of condensation is withdrawn from the steam-chest through a pipe. (Not shown.) The steam-chest j is secured to the frame A in such a position as to be directly above the endless apron O, so as to dry the articles as they are being carried out of the machine by the endless apron O.

If desired, another steam-chest may be placed between the upper and lower parts of the endless apron O, to insure the thorough drying of the articles as they are carried upon the said endless apron.

By omitting the frame b and its attachments and the steam-chest j the machine may be used as a clothes-wringer, the clothes being carried to the rollers B C by the endless apron S and delivered from the machine by the endless apron O, the tubs being placed at the ends of the machine.

Having thus described my invention, I claim as new and desire to secure by Letters Patent—

1. The combination, with the frame A and the endless apron S, of the sliding frame b, the endless apron d, the rollers a c, the gear-wheels X Y Z, and the pulleys and band U V W, substantially as herein shown and described, whereby the endless apron d is driven from the roller C to feed the articles to the endless apron S, as set forth.

2. The combination, with the frame A and the sliding frame b, that carries the rollers a c and endless apron d, of the foot-lever e, the rock-shaft f, the arm g, the rod h, and the spring i, substantially as herein shown and described, for moving the frame b and its attachments forward and back, as set forth.

JOHN VANDERCAR.
